Watson E. Coleman

UNITED STATES PATENT OFFICE.

CLARENCE L. JOHNSON, OF LITTLETON, COLORADO.

TIRE BOOT AND FASTENER THEREFOR.

Application filed November 20, 1926. Serial No. 149,709.

This invention relates to tire boots.

An important object of the invention is to provide a novel and efficient means for connecting together the edges of the boot, so that the boot may be maintained in proper position.

A further object of the invention is to so construct the boot that the connecting element may be readily attached thereto and the inner tube is protected against wear or destruction by engagement with said connecting element.

These and other objects I attain by the construction shown in the accompanying drawings, wherein for the purpose of illustration is shown a preferred embodiment of my invention and wherein:—

Figure 1 is an inside elevation of a tire boot constructed in accordance with my invention;

Figure 2 is a transverse sectional view on the line 2—2 of Figure 1;

Figure 3 is an enlarged fragmentary side elevation showing the sections of the connector separated;

Figure 4 is a plan of the blank from which the female section of the connector is formed;

Figure 5 is a similar view of the blank forming the male section of the connector.

Referring now more particularly to the drawings, the numeral 10 generally designates a tire boot, the body portion 11 of which is relatively thick at the central portions of its side edges. From this central portion, the boot is tapered to a fine or feather edge at the ends thereof. To the inner face of the body adjacent one longitudinal edge thereof is secured one edge of a flap 13 of sufficient length to bridge the gap between adjacent edges when the boot is in the closed or normal position.

A fastener for connecting the edges of the boot to one another is provided and comprises male and female sections 14 and 15. The male section 14 comprises a relatively flat body having projecting from one side thereof a series of spaced stems 16, each provided at its outer end with a transversely extending head 17. The body portion is provided with means 18 whereby it may be secured to the longitudinal edge of the boot.

In the preferred construction of the male element 14, a metallic blank is folded intermediate its end edges and from the edge produced by the fold, portions of metal are re-

moved to produce necks 16 and heads 17. From each of the strips thus produced and upon adjacent faces of these strips, tangs are struck-out to form the securing means 18, these tangs being staggered with relation to one another.

In the initial construction, the tang bearing strips 19 are left in divergent relation to one another, so that sufficient space is provided between the adjacent faces to enable the insertion of the relatively thick portion of the longitudinal edge of the tire boot therebetween. These strips 19 are then forced together, so that the tangs 18 enter the material of the boot and firmly secure the element 14 thereto.

The female element 15 likewise comprises a strip of metal folded intermediate its end edges. With this element, the portions 20 lying at opposite sides of the fold are left in spaced relation to one another. One of the elements is provided with a series of slots 21 corresponding to the head portions of the male member and through which the head portions of the male member may be inserted to the space between the sections 20. These slots have branch slots 22 for the accommodation of the neck portion 16, these branch slots extending through the bight 23 connecting the sections 20 and into the other of the sections 20, so that the neck portions may have a limited oscillatory motion when the heads 17 are in position between the sections 20. The slots 21 are spaced from the folded edge or bight 23, so that the heads 17 must be moved transversely of the section 15 before they will properly align with the slots 21 for removal therethrough. As at this time the bight 23 edge 23 will be engaged against the edges of the sections 19, it will be obvious that this removal will be accomplished with the male and female members in parallel relation, thus preventing accidental disengagement of the sections in event one end of the fastener is cramped in any manner. The body portions 20 are provided with tangs 18 similar in construction and arrangement to the tangs of the sections 19 to permit attachment of this section of the fastener to the opposite longitudinal edge of the boot.

It will be obvious that when the fastener is in applied position, the natural strain applied by the tube will tend to separate the sections of the fastener and thus hold them more firmly in engagement with one an-

other. The flap 13 interposes between the tube and the fastener and thus prevents any abrasion of the tube which might result in injury thereto.

5 Since the construction hereinbefore set forth is capable of a certain range of change and modification without materially departing from the spirit of the invention, I do not limit myself to such specific structure 10 except as hereinafter claimed.

I claim:—

15 1. A fastener for use with tire boots and the like comprising coacting male and female sections, each consisting of a folded plate, the male section at the folded edge thereof being notched to provide outstanding necks having heads at their outer ends, the female section of the fastener being provided in one side thereof adjacent the folded edge 20 thereof with slots through which said heads may pass and branch slots for the passage of said necks connecting with the first named slots of the female section and extending

from the first named slots to and through the folded edge of the plate.

2. A fastener for use with tire boots and the like comprising coacting male and female sections, each consisting of a folded plate, the male section at the folded edge thereof being notched to provide outstanding necks having heads at their outer ends, the female section of the fastener being provided in one side thereof adjacent the folded edge thereof with slots through which said heads may pass and branch slots for the passage of said necks connecting with the first named slots of the female section and extending from the first named slots to and through the folded edge of the plate, the free edges of said plates being provided upon the adjacent faces thereof with tangs for engagement in the edges of members to be connected.

In testimony whereof I hereunto affix my signature.

CLARENCE L. JOHNSON.
